UNITED STATES PATENT OFFICE.

JULIUS PEGEL, OF CAMDEN, NEW JERSEY, ASSIGNOR TO JOHN BROMLEY & SONS, OF PHILADELPHIA, PENNSYLVANIA.

DESIGN FOR A RUG.

SPECIFICATION forming part of Design No. 17,636, dated August 16, 1887.

Application filed June 20, 1887. Serial No. 241,929. Term of patent 3½ years.

To all whom it may concern:

Be it known that I, JULIUS PEGEL, a subject of the Emperor of Germany, residing at Camden, in the county of Camden and State 5 of New Jersey, have invented and produced a new and original Design for a Rug; and I do hereby declare that the photographic print accompanying this specification conveys to any one skilled in the art a clear understanding of 10 the same, and is sufficient to enable such person to use my invention.

The leading feature of my design consists in a center panel having massed a floral representation on a mottled ground. At each end of the panel are ornamental cross-strips or borders. The whole is surrounded by an ornamental border, as shown.

What I claim as my invention is—

The design for a rug herein described and shown, consisting of a center panel with 20 massed floral representations on a mottled ground, and at each end ornamental cross-strips or borders, the whole surrounded by an ornamental border, as shown.

JULIUS PEGEL.
